UNITED STATES PATENT OFFICE.

ANTHONY K. PETRON, OF AMSTERDAM, NEW YORK.

ARTIFICIAL ARM.

1,299,505.

Specification of Letters Patent.

Patented Apr. 8, 1919.

Application filed October 21, 1918. Serial No. 258,978.

To all whom it may concern:

Be it known that I, ANTHONY K. PETRON, a citizen of Russia, residing at Amsterdam, in the county of Montgomery and State of 5 New York, have invented certain new and useful Improvements in Artificial Arms, of which the following is a specification.

The primary object of the invention is the provision of an artificial arm which is readily attached to the body of a person such as 10 a soldier for use in place of an arm which has been severed.

A further object of the invention is to provide an artificial arm having jointed finger 15 members provided with finger nails, the construction being such that the elbow joint of the arm is resiliently maintained outstretched capable of being readily bent when desired, suitable weight and rigidity being 20 also imparted to the member which has a general appearance of a human arm and hand.

With these general objects in view the device consists of the combination and arrangement of parts hereinafter more fully described and illustrated in the accompanying drawings in which like reference characters designate corresponding parts throughout the several views.

30 In the drawings,

Figure 1 is a central longitudinal sectional view through the invention with a portion of the attaching means therefor illustrated in elevation,

35 Fig. 2 is a transverse sectional view taken through the upper arm upon line II—II of Fig. 1,

Fig. 3 is a similar detail sectional view upon a different line of section from that 40 shown in Fig. 2,

Fig. 4 is a vertical longitudinal detail sectional view taken upon line IV—IV of Fig. 3,

Fig. 5 is a perspective view of a portion 45 of the upper part of the skeleton member or frame of the upper arm,

Fig. 6 is a side elevation of the skeleton or frame for the arm,

Fig. 7 is a rear elevation thereof,

50 Fig. 8 is an enlarged view of a portion of the same with the hinged joint shown in section,

Fig. 9 is a perspective view of a brace employed with the frame,

Fig. 10 is a view illustrating one complete 55 arm with the manner of attaching the same to the body,

Fig. 11 is a similar view of a pair of arms,

Fig. 12 is a rear elevation of a portion of one of the finger members and 60

Fig. 13 is a central longitudinal sectional view thereof.

Referring more in detail to the drawings, the skeleton work for the arm includes an upper frame having side bars 10 hinged to 65 the similar side bars 11 of a lower frame, the said frames forming the inner members for the upper and lower arms with a pintle 12 connecting the same together serving as an elbow joint. A spring 13 encircles the 70 pintle 12 with its opposite ends secured as at 14 to the upper and lower frames, whereby the frames are normally maintained outstretched as best illustrated in Figs. 1, 6 and 7 of the drawings. A hand member 15 is 75 pivoted as at 16 to the lower free ends of the forearm bars 11, a plurality of finger joints 17 as well as a jointed thumb projecting therefrom. A cross plate 19 is pivotally connected between inwardly extending lugs 80 20 adjacent the upper ends of the upper bars 10, the extreme upper ends of which bars are beveled as at 21 upon their inner sides.

A closely coiled helical spring 22 encircles the upper frame secured to the side bars 10 85 thereof by means of oppositely positioned braces 23 in the form illustrated in Fig. 9 of the drawings, screws 24 extending through the braces 23 and into the adjacent portions of the bars 10 for holding the members together.

In a similar manner, a helical spring formed of resilient wire, closely coiled into a slightly tapered casing 25 surrounds the lower arm being attached by screws 24 to 95 the lower bars 11 in a similar manner, it being understood that the casings 22 and 25 are of similar tapered construction giving the general form of an arm member to the structure.

An envelop or covering 26 of flexible material and preferably of a slightly resilient form of rubberized or other suitable material is drawn over the casings 25 and 22 with a hand portion 27 of the covering in the 105 form of a glove closely fitting the hand 15 with its fingers 17 and thumb 18 of the skeleton structure. A suitable filling 28 of

such material as coiled or tangled wire, metallic hair or other material is packed or padded as a lining between the covering 26 and the casings 25 and 22 giving the appearance and form of a lower and upper arm.

An attaching collar or jacket 29 of the same material as the covering 26 is provided at the upper end thereof for encircling the shoulders of the wearer being secured by 10 means of suitable lacing 30 and when only one artificial arm is employed, having an open arm-hole 31 at one side thereof for receiving the arm of the wearer therethrough. When the jacket is positioned upon the person, the shoulder portion or stump of the arm is to be seated upon the plate 19 of the upper arm framework between the beveled portions 21 of the bars 10 and by moving this 15 stump portion, the artificial arm may be 20 swung around as found desirable.

When the elbow portion is bent manually by the wearer, the spring 13 will normally return the arm to its outstretched position when released. Terminal plates 32 are provided at the ends of the finger portions of 25 the glove 27 serving as or giving the appearance of finger nails to the artificial digits.

Where two artificial arms are provided in this manner as illustrated in Fig. 11 of 30 the drawings, the jacket portion 29' is attached to both of the arms as 26 and 26' while the jacket is being secured around the neck and upon the shoulders of the wearer,

both arms are secured in their operative positions.

The material of which the covering 26 is formed is such as to be water-proof so as to be washed whenever desired and the color thereof may be that of human flesh for presenting the appearance of the natural arms. 40

What I claim as new is:—

An artificial arm comprising an upper frame formed of side bars, a lower frame having side bars hinged to the side bars of the upper frame, spring connections between 45 said frames whereby the latter are normally maintained outstretched, inwardly projecting lugs spaced from the upper ends of the bars of the upper frame, a plate connecting the said lugs, the upper ends of the bars of 50 the upper frame being beveled adapted for the reception of the stump of an arm therebetween for seating upon said plate, a hand member pivoted to the lower end of the lower frame, closely coiled springs encircling the upper and the lower frames, securing means between the said springs and frames, a resilient packing surrounding the said springs, an envelop covering said packing with a glove portion surrounding the 55 said hand, and a jacket attached to said envelop adapted for attachment to the human body.

In testimony whereof I affix my signature.

ANTHONY K. PETRON.
